UNITED STATES PATENT OFFICE.

BENJAMIN S. BENSON, OF BALTIMORE, MARYLAND.

TRACTION-ENGINE.

SPECIFICATION forming part of Letters Patent No. 249,451, dated November 15, 1881.

Application filed March 8, 1881. (No model.)

To all whom it may concern:

Be it known that I, BENJAMIN S. BENSON, of Baltimore city, State of Maryland, have invented certain new and useful Improvements 5 in Traction-Engines; and I hereby declare the same to be fully, clearly, and exactly described as follows, reference being had to the accompanying drawings, in which—

Figure 1 is a side elevation of the traction-engine. Fig. 2 is an end elevation, partly in section, the part to the right of the dividing-line being a section on the line $x x$ of Fig. 1, while that to the left of the same is a section on the line $y y$ of the same figure. Fig. 3 is a 15 plan, partly in section, of one-half of the engine. Fig. 4 is a sectional view of the differential clutch. Fig. 5 is a plan and elevation of a sprocket-wheel link. Fig. 6 is an elevation, partly in section, of a track-link, its tie-rod, 20 and foot. Fig. 7 is a plan, on a reduced scale, of the parts shown in Figs. 5 and 6. Fig. 8 shows plans and a section of the parts of the device I make use of for steering the engine.

My present invention relates to traction-engines; and it has for its object to obviate the 25 difficulties which have heretofore been encountered in the use of devices of that class and provide an engine which, aside from embodying radical departures in detail from the conventional machines of the same general class, shall, as a whole, be more efficient and satisfactory than the same, more easily guided and steered, and of such adaptability as regards the supporting feet and trucks as to be practically independent of roughness or inequality of surface.

In describing the machine illustrated in the accompanying drawings I shall, for the sake of perspicuity, and to prevent the loss, on the 40 reader's part, of the thread of the co-operation and coaction of the parts, treat first of the construction and operation of the engine as a whole and in general terms, and then proceed to describe in detail such parts of the same as merit further reference. For the sake of brevity, and to avoid tautology, I make at this point no formal statement of invention, but state that the invention is made the subject of the 45 claims.

50 Referring, now, to the accompanying drawings, and in particular to the first three sheets of the same, A is the main frame of the en-

gine, consisting of four longitudinal beams, 55 suitably braced laterally by ties and beams H 18. On the frame are supported the boiler B and the engine. (The latter not shown.) Between the beams A on either side of the engine are two trucks, having flanged wheels f , whose axles are journaled in bearings on the stringers a , which sustain the bolsters 18 of 60 the rear trucks and the supporting-beams 17 of the forward trucks. The bolsters and beams do not rest directly upon the stringers, but upon cross-beams 15, which are V-shaped on 65 their upper faces in order to permit the trucks to play freely laterally. Pins or king-bolts 16 connect the beams 15 with the bolsters 18 and supporting-beams 17. Be it understood, in a word, that the trucks have a freedom of motion within the beams A, both as regards a 70 swiveling motion about their bolts and a tilting motion laterally and fore and aft. They are only restrained as to bodily motion longitudinally or laterally. The trucks rest upon an 75 endless railway composed of a series of links, C, connected by tie-rods D, which are curved downward and have attached to their lower ends the supporting and traction feet d . The curved ends of the tie-rods extend backward, 80 as shown, and are connected with the links near their opposite ends by braces b . Bow-string braces 32 connect the rods D near their lower ends and serve to prevent them from spreading under the weight and traction-strain.

Midway between the track-links (see Fig. 7) 85 is a sprocket-chain of peculiar construction, as hereinafter set forth, the cross or tie rod serving as the cross-pin for every fourth link. The chains pass over sprocket-wheels 1 at each end of the main frame, which wheels are driven by 90 a train of gearing arranged as follows: The crank 19 is mounted on a shaft, 19, that carries a pinion, 11, a sprocket-wheel, 12, and the fly-wheel 10, the latter being on the opposite side of the machine from the crank and engine, 95 so as to preserve trim. The pinion 11 meshes with a wheel, 13, which is loose on the shaft 14, which latter carries a friction-clutch, 33, which may be used as a brake in running down hill either alone or in connection with a similar 100 clutch on the wheel 8. (Not shown.) From the shaft 14 motion is communicated, in a manner hereinafter more fully set forth, to the pinion 21, which drives the wheel 22, that is keyed on

the rear sprocket-wheel shaft, 2. The corresponding shaft 2' on the other side is in alignment with the shaft 2, and is connected with it by a loose sleeve 20. From the sprocket-wheel 12 a chain runs to a sprocket-wheel, 8, on the shaft 7, which latter carries a smaller sprocket-wheel, 6. This latter drives the sprocket-wheel 1 at the front end of the engine through the medium of the sprocket-wheel 5 and gear-wheels 4 and 3. These wheels are, of course, of such relative size that the two wheels 1 at the opposite ends of the engine revolve in the same direction and at the same speed. To the end that the machine may be turned in a curve it is, of course, necessary to cause the plane of the forward sprocket-wheel to incline to the axis of the machine, and this end I attain as follows: The wheels 1, 3, 4, and 5 are mounted in bearings on a frame, I, pivoted to the cross-beam H at i and hinged at 34, so that they are capable of a swinging motion from side to side and of a rising-and-falling motion in a vertical plane, the latter being designed to admit of the machine being run over rough ground.

A tongue, G, having double and single trees adapted for the attachment of horses when the device is to be drawn after the manner of an ordinary vehicle, is pivoted to the beam H and carries a threaded sleeve, 35, through which passes a screw-rod, 36, carrying a wheel, 37, from which a drive-chain leads to another wheel in convenient reach of the driver's seat.

To the tongue G is pivoted a cross-bar, g, that is connected by pivot-joints 38 to the curved ends of the frames I at either side. In Fig. 3 but one-half the engine is shown. The frame I and gear-wheels 1, 3, 4, and 5 are duplicated on the side not shown. The ends carrying the bearings of the shafts 2 normally rest on the ends of the beams A.

It is obvious that upon turning the wheel 37 the rod 36 is screwed into or out of the sleeve 35 and swings the two frames I to the right or left. The incident version of the planes of the sprocket-wheels 1 results in laying the track-links in a curve, and the trucks of the wheels swing accordingly, turning the machine. Obviously a great precision and nicety of steering result. This steering mechanism may be used alone or in connection with that at the rear of the machine.

Such is, in general terms, the construction of the engine.

In operation, the wheels 1 being caused to turn, the chains E are drawn along, carrying the track-links C, ties D, and feet d. The trucks run upon the lower links, C, and the machine is guided at will by the steering mechanism, the described construction of which sufficiently explains its operation. In backing the machine it is impracticable to steer from the normal front end, so I make use of the device at the rear end, the construction of which is as follows:

The parts 23 on the shaft 14 (illustrated in

detail in Fig. 8) are described in detail in application of even date herewith, but a brief description of the same may here be given. The object of the device is to cause one side of the machine to travel faster than the other, so that the tracks will be laid in a curve.

The pinion 21, which communicates motion to the sprocket-wheel, is loose on the shaft 14, and to it is secured a spiral pinion, 78, which meshes with a similar pinion, 77, that is mounted in a casing, 71. The shaft of 77 is inclined, as shown, and on it is mounted a crown-gear, 74, with the teeth of which a spiral, 76, on the shell 73 engages.

72 is a spring which bears against the shell 73 and causes it to turn with the part 71. 75 is a strap-brake on the periphery of the shell 73. On gripping this shell by means of the brake it is held stationary while the revolution of the shaft 14 carries the crown gear 74 around in engagement with the spiral 76. As a result, at each revolution one tooth passes the spiral and a positive revolution is imparted to the wheels 77, 78, and 21 independent of that of the shaft 14, whereby the gearing connected with 21 travels faster than that on the other side of the machine, and the track is laid in a curve. 28 is a duplicate of 23, and to the disk of each is secured a sleeve, 24, carrying bevel-gear wheels 17 and 25, which mesh with a wheel, 26, that turns on a pin integral with a boss, 39, that is keyed to the shaft 14 between the wheels 17 and 25.

A cogged rod, 42, slides within the shaft 14, and meshes with a pivoted lug, 40, having teeth 41. Upon thrusting the rod 42 inward the lug 40 engages with the wheel 17, locking it and the wheel 25 with reference to the shaft 14, when the rear sprocket-wheels may be turned at the same rate of speed. By means of the differential clutches the sprocket-chains may be driven faster or slower on one side than on the other and steer the machine with great nicety either forward or backward.

Proceeding, now, to describe certain parts in detail, and referring to Figs. 5 and 7, E is the drive or sprocket chain, consisting of a double row of links, having an enlarged center, 43, and internal lugs 44 on every other pair in the length of the chain. The pins 45 have heads 47 and a reduced portion, 46, of a width equal to double the thickness of the link E. The internal diameter of each link at the end is equal to the thickness of the part 46 of the pins, while the opening 43 is of sufficient size to admit the head. To put the links together the pins are thrust through the central portions, 43, of four links, of which the middle pair are drawn to one side and the outside links to the other, bringing the pin into the end of the links, where the latter are properly held apart by the shoulders and heads of the pins, as shown. The lugs 44 serve to space the central opening between the most widely-separated links and enter the chain properly on the wheel.

In Figs. 6 and 7 are shown the tie-rod, braces,

track-links, and traction-feet. Describing them in the order named, the tie-rods D pass through holes 55 in the ends of the links C and are bent downward and backward at 48 and again at 49, meeting the feet d at right angles. Between the track-links C the tie-rods pass through the sprocket-chain and constitute the transverse pins at those points, the links being held in place by collars 50. The braces b connect the lower ends of the tie-rods with the opposite end of the links C, and the rods are connected transversely by bow-string braces 32. The object of springing the tie-rods outward is to cause the feet in passing forward to overhang the machinery, so that any dirt that may be carried up by the feet will not fall on the wheels or chains.

The track-links are of malleable iron or steel, and have holes in their forward ends, through which the rods D pass. At their rear ends they have elongated slots, 56, through which the tie-rod of the next track-link passes. This feature is most important, as it enables the tie-rods to move backward at one end, as the tracks are laid in a curve, and enables me to use a very small sprocket-wheel at either end, as the tie-rods in passing over the wheel slide back in these slots, so that the links, instead of lying close to the periphery of the wheel, constitute 30 cords of its circle almost equal in length to its diameter, as clearly shown in Fig. 1. The intermediate links of the drive-chain of course remain tense about the periphery of the wheels, obviating all danger of the pins sliding back to the central opening of the links and falling out.

The feet d may, perhaps, be most accurately described by likening them to inverted mushrooms or saucers. They are circular in cross-section and have a rim-flange and transverse rib, 51, to prevent slipping. The boss 52, which serves as the step for the end of the tie-rod D, is hollowed internally to the shape of a sand-glass, the rod D nearly fitting in the narrowest part, where a pin, 54, passes through boss and rod, holding them in place. A ball, 53, is placed under the rod within the boss, and on it rests the end of the rod. It will thus be seen that the foot can play freely in any direction to the extent permitted by the conical hollowing of the boss, and it always swings to a horizontal position as it approaches the ground in front, or at the rear in backing, and meets the ground squarely.

55 Touching details of construction, it only remains to add that the rear sprocket-wheels, 1, are made susceptible of being lifted to ride over inequalities of the ground, having their journals in the ends of the bars 58, that are pivoted to the beams A at 59. Guides 60, secured to the beams, serve to hold the bars 58 and prevent them from being laterally displaced, while allowing them to rise and fall freely. The friction-clutch 33 is a simple toggle-joint brake adapted to press upon the inside of the flange of the wheel 13. It is a well-known mechanical

device and needs no further illustration nor description.

In order to give a slight play to the tie-rods, to allow for the movement of the feet with reference to the track-links, the tie-rods are divided, as shown in Fig. 7, and are connected by a sleeve, 110, having a set-screw. The set-screw enables me to secure the parts of the tie-rod rigidly together when traveling on level ground, or to cast it loose when moving over a rough surface.

By reason of the adaptation of the various parts of the engine to travel over rough ground, it is eminently fitted for use in connection with a gang-plow, one of which I have devised for use with the engine, and have made the subject of a separate application for Letters Patent.

What I claim is—

1. In a traction-engine, a main frame provided with swiveling trucks and an endless railway, whereby the trucks are free to swing, in order to conform to the curve in which the track is laid, as set forth. 85

2. In a traction-engine, a main frame provided with trucks having a universal motion about their king-bolts, and an endless railway, as and for the purpose set forth. 90

3. In a traction-engine, a main frame provided with swiveling trucks having flanged wheels, and an endless railway having traction-feet, as set forth. 95

4. In a traction-engine, an endless railway provided with cross-ties having laterally-springing traction-feet, as set forth. 100

5. In a traction-engine, a main frame having at each end a sprocket-wheel and gearing intermediate the same and the engine, whereby either wheel may be driven independently of the other, a pair of flanged-wheel swiveling trucks, and an endless railway, as set forth. 105

6. In combination with the main frame and trucks, the track-links, cross-ties, and sprocket-chain, the latter being intermediate the track-links, as set forth. 110

7. In combination with the main frame and trucks, the sprocket-wheels at each end susceptible of a rising-and-falling motion with reference to the frame and an endless railway and traction-feet, as set forth. 115

8. In combination with the main frame, the front sprocket-wheel frame, pivoted and hinged so as to swing laterally and vertically, as set forth.

9. In combination with the main frame having guides 60, the pivoted bars carrying the journals of the rear sprocket-wheel, as set forth. 120

10. In combination with the main frame consisting of four parallel beams supported upon four swiveling trucks, the endless track and traction-feet and driving mechanism, as set forth. 125

11. In a traction-engine, an endless track consisting of a series of links having elongated slots 56, whereby the track may be laid in a curve, as set forth. 130

12. In combination with the endless track,

- the tie-rods D, curved rearward, downward, and outward, as set forth, and having the traction-feet d.
13. In combination with the curved tie-rods, 5 the traction-feet pivoted to the ends of the rods and having steps 52, as set forth.
14. In combination with the track-links and sprocket-chain, the tie-rods D, constituting transverse pins of the chain, as set forth.
15. In combination with the track-links, the sprocket-chain consisting of links having enlarged central openings, 43, and shouldered pins 45, as set forth.
16. The endless track consisting of the track-links having slotted ends, the curved tie-rods passing therethrough, and the traction-feet pivoted to the ends of the tie-rods, as set forth.
17. In combination with the track-links, the links E, having internal lugs, 44, the headed and shouldered pins 45, as set forth.
18. In combination with the tie-rods D, curved rearward, downward, and outward, and having traction-feet d, the bow-string braces 32, as set forth.
19. In combination with the links C, having holes 55 and slots 56, the curved tie-rods D, having traction-feet d and braces b 32, as set forth.
20. In combination with the main frame, having front sprocket-wheels mounted in laterally-movable bearings, mechanism for simultaneously inclining the planes of the sprocket-
- wheels to the axis of the engine, whereby the track is laid in a curve, as set forth.
21. In combination with the main frame, having tongue G, the frame I, bar g, rod 36, sleeve 35, and actuating mechanism, as set forth.
22. In combination with the driving mechanism and shaft 14, the differential clutches 23 28, and clutch intermediate the same, as set 40 forth.
23. In a traction-engine, a sprocket-wheel and track composed of links having slotted ends and a sprocket-chain intermediate the track-links, whereby the chain conforms to the 45 periphery of the wheel and the slotted links cross the faces of the wheel, as set forth.
24. In combination with the shaft 14 and sleeves 24, the differential clutches 23 28, wheels 17 25 26, and pivoted lug 40, as set forth.
25. In combination with the traction-feet having steps 52, and the tie-rods D, the balls 53, as set forth.
26. In combination with the traction-feet and track-links, the divided tie-rods D and 55 sleeves 100, having clamping-screws, as set forth.
27. In combination with the traction-feet and track-links, the divided tie-rods D and sleeves 100, having clamping-screws, as set forth.
